(57) **CLAIM**

The ornamental design of a surface-mounted applicator device, as shown and described.

DESCRIPTION

FIG. 1 is a rear perspective view of a surface-mounted applicator device in accordance with the present invention; FIG. 2 is a front perspective view thereof; FIG. 3 is a bottom perspective view thereof; FIG. 4 is a rear view thereof; FIG. 5 is a front view thereof; FIG. 6 is a right side view thereof; FIG. 7 is a left side view thereof; FIG. 8 is a top view thereof; FIG. 9 is a bottom view thereof; and, FIG. 10 is a wall-mounted front perspective view thereof. The broken lines shown in the drawings represent portions of the surface-mounted applicator device that form no part of the presently claimed design.
